VENTILATOR STRUCTURE

Frederick N. Ross, Detroit, Mich.

Application April 10, 1933, Serial No. 665,290

5 Claims. (Cl. 98—94)

The subject matter of the present invention 5 reposes in a ventilator structure, casement windows or doors, and/or windows or doors of the type having lights or sections of glass divided by mullions or the like running vertically, horizontally, or in both directions.

Much emphasis is being directed at the present time to the subject of ventilation, particularly of residences and the like; also casement windows 10 and such like are increasing in popularity, especially in residences. Heretofore much concern has been given to the problem of equipping a casement type window, or a window with mullion bars with a ventilator. Particular reference is made 15 to a ventilator having a fan and an electric motor for operating the same. It is believed that up to the present time no satisfactory arrangement has been devised.

The present invention aims to provide an arrangement which involves principally a novel 20 manner of mounting a ventilator in a window or the like having a plurality of lights or panes of glass divided by mullions, and the window may or may not be of the casement type, although the 25 present steel structure for windows which have mullions usually embody also a casement type of structure. The invention is concerned particularly with steel window frames having steel mullions and which may be of the casement type and it further involves a novel structure in a 30 ventilator by means of which the same may be readily mounted.

Fig. 1 is an outside view of a window of a 35 building of the type having a steel frame with mullions and having a hinged section which is openable and which may be termed a casement window, showing the ventilator.

Fig. 2 is an inside partial view thereof showing the ventilator.

Fig. 3 is a vertical sectional view taken through 40 the ventilator window and portions of the building structure.

Fig. 4 is a horizontal section taken substantially on line 4—4 of Fig. 5.

Fig. 5 is an enlarged inside view of a portion of 45 a window and illustrating certain details of structure.

Fig. 6 is a vertical section through the ventilator 50 illustrating structural features and showing how the motor and fan may be movably mounted.

Fig. 7 is an inside view of the ventilator frame with motor and fan removed.

Fig. 8 is a small view illustrating a portion of a 55 window on the outside without a ventilator mounted therein.

First referring to Fig. 1, the particular window shown has a frame 1 and a plurality of lights or sections of glass 2 divided by vertical mullions 3 and horizontal mullions 4 and the frame and mullions may be of metal such as steel with the 5 glass panels sealed in any well-known manner with putty, lead or other suitable sealing material or cement. For the purpose of convenience the term "putty" will be used largely herein and this is to be construed broadly as a word covering 10 any material suitable for the purpose. The window may have a casement section which consists of a frame 5, horizontal mullions 6, and vertical mullions 7 dividing the glass panels, which section may be hinged as at 8 so that the same 15 may be opened. This figure shows a ventilator generally illustrated at 10 mounted on the upper portion of the window with lights or glass panels 11 on either side thereof. Without the provision 20 of the ventilator the window would have, instead of small lights 11, two lights identical with the lights or glass parts 2 divided by a vertical mullion 3a. This is illustrated in Fig. 8.

A view from the inside is shown in Fig. 2, and 25 a consideration of the reference characters on that figure will readily identify the parts with those seen in Fig. 1. The invention may be carried out by installing the ventilator in a window frame which originally was not so equipped, in which event one of the mullions may be removed, 30 as for example the center uppermost mullion 3a as shown in Fig. 8. Likewise the glass panels 2 on either side thereof may be removed, and then the ventilator installed and the smaller panels 11 installed if the same were necessary. The 35 invention may be carried out by originally equipping a window with a ventilator.

Refer now to Fig. 3; Certain structural details of the building are shown, as for example, the brick 15, stone 16, these being on the outside, and on the inside plaster 17 and sill 18. The frame 1 which in cross section may approximate a Z-shape is suitably fastened in position and it may be sealed by a suitable putty or mastic 19, and a metal strip 20 may be applied to drain off the water. The frame 5 is 40 illustrated in closed position with the glass panels 2 cut through to shorten the view, and after the usual fashion, the glass is sealed in by putty 21.

The ventilator passageway may be provided by 50 two telescoping members, the inside one being shown at 25 (Fig. 6) having an upper flange 26 adapted to be secured to the frame member 1 as by means of screws or the like 27. This member likewise has a lower flange 28 which may be 55

fastened to frame member $1a$ by screws or the like 29 . These screws pass through apertures in the frame and may thread into bosses 30 on the frame member.

5 Refer now to Fig. 4: It will be seen that the frame member 25 has a flange 31 on opposite sides and also preferably has the flange-like part 32 , the two flanges cooperating to form an L-shaped panel. The mullions 3 , as shown in Fig. 4, 10 may be T-shaped in cross section; accordingly, the parts 31 and 32 constitute what may be termed half a mullion. The member 25 has a central aperture extending therethrough bounded by walls 33 .

15 The other member of the ventilator is illustrated at 34 and it may telescope with member 25 and this member also preferably carries openable closure members or louvers 35 which are closed as shown in Fig. 6 and at least partially 20 open as shown in Fig. 3, and which may be opened and closed by means of a lever 36 through mechanism which is not shown.

The fan is shown at 40 mounted on a shaft of motor 41 carried on a frame 42 . The frame may 25 be pivotally connected to the member 25 as at 43 , and it may be detachably connected at a point diametrically opposite the hinges 43 by means of a thumb screw 44 (Fig. 3). A screen 45 carried by a ring 46 may cover the motor and fan and 30 it may be secured to the member 26 by thumb screws 47 (Fig. 5). An electrical switch for controlling the operation of the motor is shown at 48 (Figs. 4 and 5). The two members 25 and 34 35 may be secured together as by means of screws 50 advantageously located outside of the central passageway as illustrated in Fig. 5, passing through the member 25 and into internally screw-threaded bosses 51 carried outside a tubular extension 52 of member 34 . At this point it 40 may be mentioned that the central aperture in member 25 may be circular so as to substantially fit the fan although the member 25 in overall dimensions may be rectangular or square. Likewise the tubular extension 52 of member 45 26 may be circular for fitting over the central circular portion of member 25 while the outer end carrying the louvers may be rectangular or square. The members may be drawn together by the screws until flange 53 of member 25 butts against member 34 , as illustrated in Fig. 3.

50 Let it be assumed that a window, such as shown in Fig. 8, is already installed in a house and it is desired to equip the same with a ventilator. The mullion $3a$ may be removed, preferably after 55 having first removed the glass panels on either side thereof. The mullions are usually separate pieces having their parts interfitting with the horizontal frame members or mullions. The only modification needed in the frame is the provision of apertures. Two of them may be drilled 60 through the frame member 1 on centers designed to take the screws 27 ; two apertures may be drilled through the frame member $1a$ designed to receive screws 29 . The ventilator may 65 now be located and to seal the same, putty or the like may be used, as illustrated in Fig. 3, and then the screws 27 and 29 are positioned. Thus by these simple expedients the ventilator structure is mounted in the window frame. The 70 glass panels 11 may now be inserted; these may be cut from the glass previously removed or brought to the job by the workman if he knows before hand what dimensions are needed. The glass panels 11 may now be inserted as shown in Fig. 4, each being held on one vertical edge

75 by the mullion strips 3 , and on the opposite vertical edge by the L-shaped recesses or half mullions provided by the ventilator frame, and they may be sealed in by putty 21 after the usual fashion. This completes the job and the structure is ready to operate. Window frames may be made up with the screw holes already drilled so that at any time either at initial installation or subsequently thereto a ventilator may be easily installed. The simplicity of the 10 structure and mounting is again emphasized; to mount the ventilator all that is needed is to remove a mullion strip to secure the ventilator in the frame and then glaze the frame on opposite sides of the ventilator. 15

The present disclosure shows the ventilator mounted in a portion of a window which is not hingedly mounted. It is entirely feasible, however, to mount the ventilator in a hinged frame and this will be readily appreciated by reference 20 to Fig. 1, where it will be seen that the ventilator may be mounted, for example, in the upper section of the hinged section by removal of the upper mullion 1 , the upper glass panels on either side thereof, and then the mounting of the ventilator and smaller panels in place. The structure is of a compact nature and the motor may lie inwardly of a vertical plane coinciding with the face of the plaster 11 so that a window shade may be readily lowered without interference by 30 the ventilator structure or the motor.

In use, the ventilator may be controlled by the switch 48 carried by the ventilator frame, and the louvers may be opened and closed by operation of the lever 36 . The louvers may be opened 35 with or without motor operation. Access may easily be had to all parts for cleaning as follows: by removing the thumb screws 47 the screen may be taken off and then by loosening thumb screw 46 the motor and fan may be 40 swung to a position as shown in Fig. 6 which affords access to the passageway, the louvers and the fan itself.

I claim:

1. A ventilator for a window or the like having 45 horizontal frame members and vertical mullions for dividing window panes comprising, a supporting structure for a fan having vertical edges and having an aperture therethrough and adapted to fit between two of said horizontal frame members one above and one below the supporting structure and to be secured thereto, the vertical edges of the supporting structure being spaced from vertical mullions of the window frame, and means on the vertical edges of the 50 supporting structure forming L-shaped recesses which constitute substantially one-half a mullion form for receiving each the edge of a pane of glass with each pane of glass positioned between said edge and the next adjacent vertical mullion 55 of the window frame.

2. A ventilator structure for a window or the like having horizontal frame members and vertical mullions for separating panes of glass, said frame members and mullions having flange parts 60 for backing up panes of glass mounted therein by the means of putty or the like comprising, a supporting structure for a fan having at its upper and its lower edges formations adapted to fit against the portions of two of said horizontal frame members which were designed to receive the edges of panes of glass, said formations being substantially the counterparts of the edges of panes of glass, said supporting structure having side edges each having a flange-like mem- 75

ber and spaced from the next adjacent vertical mullions presenting in cross-section an L-shape, constituting substantially one-half a T-shaped mullion and adapted to receive the edges of panes of glass, with said panes of glass positioned between said edges and the next adjacent vertical mullions.

5. A ventilator for a window structure or the like having channeled members designed to receive the edges of panes of glass and having vertical mullions, a supporting structure having upper and lower parts which are substantially counterparts of the edges of panes of glass which are adapted to be substantially received by the 10 channeled frame members and to be secured thereto, said supporting structure having side edges with portions presenting an L-shape in cross section and spaced from next adjacent vertical mullions of the window frame and adapted 15 to have edges of panes of glass sealed therein by putty or the like.

10. In combination, a window or the like having horizontal frame members and vertical mullions dividing panes of glass, a ventilator having 15 a frame portion of rectangular shape having upper and lower edges arranged to be received in the frame members in place of glass panes and 20 to be secured thereto, opposite vertical edges 25

thereof being spaced from next adjacent vertical mullions, said supporting structure having on its opposite vertical edges means forming substantially one-half a mullion, and panes of glass mounted in the frame each having one edge sealed to a vertical mullion next adjacent the vertical edges of the supporting structure and an opposite edge sealed to the said means on the vertical edges of the supporting structure.

5. In combination with a window structure or the like having horizontal frame members and vertical mullions for receiving edges of panes of glass, a ventilator structure comprising a supporting member having at its upper edge a portion received in a horizontal frame member in 10 place of a pane of glass and having at its lower edge a portion received in a horizontal frame member, the supporting member having vertical side edges spaced inwardly from next adjacent vertical mullions, and each having a groove for 15 receiving the edges of a pane of glass, and a pane of glass on each side of the supporting member each having its upper and lower edges mounted in said horizontal frame members and having one vertical edge mounted in the next adjacent vertical mullion and its other vertical edge mounted 20 in a groove in the supporting member.

FREDERICK N. ROSS.
